UNITED STATES PATENT OFFICE.

EDWARD L. HOLMES, OF BERKELEY, CALIFORNIA.

PHONOGRAPH.

1,391,543.

Specification of Letters Patent. Patented Sept. 20, 1921.

Application filed July 26, 1915, Serial No. 41,900. Renewed March 29, 1919. Serial No. 287,660.

To all whom it may concern:

Be it known that I, EDWARD L. HOLMES, a citizen of the United States, residing at Berkeley, in the county of Berkeley and 5 State of California, have invented new and useful Improvements in Phonographs, of which the following is a specification.

This invention relates to phonographs, and has for its object to produce a machine of 10 this character which will be entirely automatic in its operation to effect the repetition of the whole or any selected portion of a record, to disconnect the reproducer from the record and stop the latter at any prede- 15 termined position in the progress of playing, and to start it when the parts are moved to playing position.

This and other objects, which will later become apparent, I accomplish by means of 20 mechanism which may be set either before or during the course of playing to automatically disconnect the reproducing device from the record and stop the movement of the record, or to move the parts to position for 25 automatically repeating a whole or any portion of the record, and acting also to automatically start the record when the reproducing device is moved to playing position.

One form which my invention may assume 30 is exemplified in the following description and illustrated in the accompanying drawings, in which—

Figure 1 shows a plan view of a disk phonograph, of the swinging free arm type, 35 embodying my invention.

Fig. 2 shows a similar view with certain parts removed or broken away for the sake of clearness.

Fig. 3 shows a vertical, central, sectional 40 view of the device shown in Fig. 1.

Fig. 4 shows a view of the parts, taken on line 4—4 of Fig. 3.

Fig. 5 shows a detail perspective view of 45 the plunger head and pendent trip arm em- ployed in this device.

Fig. 6 is a view taken on line 6—6 of Fig. 3.

Fig. 7 is a view taken on line 7—7 of Fig. 3.

Fig. 8 shows a detail view in inverted plan, 50 of the locking device for the shifting mechanism.

Figs. 9 and 9^a show plan views of the actuating parts of the shifting mechanism in 55 different positions of operation and are taken on line 9—9 of Fig. 3.

Fig. 10 shows a longitudinal, central, sectional view of the air compressing plunger or dash-pot employed in my device for the purpose of cushioning the downward move- 60 ment of the tone arm.

Figs. 11 and 12 show transverse sectional views taken on line 12—12 of Fig. 10 and illustrating the action of the locking mechanism for holding the plunger in position 65 where the tone arm will be elevated.

Fig. 13 shows a perspective view of the reciprocal trip-actuating device.

Referring more in detail to the form of my invention illustrated herewith, it will be 70 seen that I employ a disk-phonograph of ordinary construction, comprising a cabinet 10, within which is carried a motor 11 for driving the vertical shaft 12, upon the upper end of which are carried the turntable 13 and record 14. The phonograph also embodies a freely swinging, pivotal tone arm 15, to which is attached the reproducing device 16 carrying a needle 17. The arm 15 is rotatable within a support 18, which support 75 may, if desired, serve also as a connection to the amplifier (not shown). It is obvious, however, that a sound horn may be connected with the tone arm independently of the support 18. 80

Within the cabinet 10, preferably hidden from view, I have provided a supporting base 19 and a bracket 20, upon which is journaled a vertically arranged stub shaft 21 carrying a segmental driving member 22. 90 The shaft 21 is preferably driven by means of a sprocket wheel and chain connection 23 from the shaft 12. On the upper end of the shaft 21 I have provided a crank arm 24, carrying at its outer end a stud 25 fitted to a scotch yoke 26, slidably mounted upon a horizontal rod 27 carried by the base plate. It will thus be seen that the rotary motion of the crank shaft is translated into a reciprocal movement by the yoke. 95

Upon the head of the yoke there is formed a slotted curved arm 28, made arcuate with respect to the vertical axis of the tone arm, and a pin 29 resides within the slot in said arm and is fixed to a slideable block 30. The block 30 is fitted into a radial slot 31, formed in a segmental plate 32, which plate has a 100 slideable movement upon a quadrant 33 struck from the vertical axis of the swinging tone arm.

To slide the segmental plate 32 within the quadrant, I provide an adjusting lever 34, 110

pivoted at 35 to the top portion of the cabinet, engaging frictionally therewith, and having one portion projecting beyond the periphery of the record turntable, which is 5 provided with a thumb-piece 36, and having another portion 34' arranged below the top of the cabinet and projecting horizontally to a position adjacent to the plate 32 where it is provided with a slot and pin connection 10 37 therewith. It will be understood from this that the adjusting lever 34 is readily accessible to the operator and, when actuated, will cause the segmental plate 32 to be moved within the quadrant and carry with it the 15 slidable block 30, which block is reciprocal within the slot 31 by means of its connection with the yoke 26, and on account of the curved, slotted head of said yoke such adjustment, laterally, of the slidable block obviously is not interfered with. Attention is 20 called to the fact that, no matter what the lateral position of adjustment of the slidable block 30 may be, its reciprocal movement always will be in a radial line with the axis 25 of the swinging tone arm on account of the quadrant 33, as described.

Upon the slidable block 30 there is fixed a wedge-shaped tripping lug 38, the apex of which points inwardly. Coöoperating with 30 this lug is a pendent trip arm 39 pivoted between a plunger 40 and link 41. The plunger is carried within a dash-pot 42 which is supported upon a bracket 43, connected rigidly by means of a strap 44 with the tone arm 15. The link 41 is slidable with the plunger and has a right angular downward extension 45, and at or near the corner thereof there is pivoted a bell crank lever 46 upwardly projecting and fulcrumed at 47 35 to the bracket 43, from which fulcrum it extends forwardly, and at its free end is provided with a roller 48 adapted to engage with the lower surface of the tone arm 15.

The operation of the structure thus far described will be as follows: The normal travel 45 of the tone arm, when the phonograph is in operation, is from the periphery of the record toward the center thereof, being actuated by the needle operating in the spiral 50 grooves of the record, and in so moving the bracket 43, on account of its connection with the tone arm, will be carried through the same path. Therefore, the pendent trip arm 39 will be carried along with the tone arm 55 until it reaches a position in line with the tripping lug 38. The arm 39 has a swinging movement in but one direction on account of a pin and lug arrangement 49, shown in Fig. 5. This arm is also provided 60 with a longitudinal groove 50 and is so pivoted as to allow a slight lateral movement. When, therefore, the said arm has been moved to a position where its groove 65 will be directly in line with the apex of the tripping lug 38 and the lug is moving

inwardly in its reciprocal path, an engagement takes place between the parts which causes the link 41 and plunger 40 to be moved inwardly with the lug. At or near the end of the inward movement a gravity locking 70 pawl 51, carried on the dash-pot 42, as shown in Figs. 11 and 12, engages with an annular depression 52 formed in the plunger and holds the latter against return movement, in which position, owing to the bell crank 75 connection 46 with the link 41, the tone arm will be raised to a position where its needle will be disconnected from the record and will be positively held in its raised position. Simultaneously with the inward movement 80 of the link 41 and plunger, the downward extension 45, carried by the said link, will be moved inwardly to the dotted line position shown in Fig. 3.

Upon the lower end of the extension 45 85 there is formed an arcuate shoe 53 lying in the same plane with the sector 22, as best shown in Figs. 9 and 9^a. The said sector, it will be understood, is being continuously rotated on account of its driving connection 90 with the motor. I preferably construct this sector with a row of brushes or bristles 54 on its periphery, and obviously with the shoe moved inwardly to the dotted line position shown in Fig. 9 it will be engaged by the 95 said bristles and swung laterally, carrying with it the bracket 43 and the tone arm 15. The direction of movement of this arm, obviously, will be outwardly from the center 100 of the record.

For controlling the shifting movement of the tone arm and associated mechanism, and for releasing the plunger 40 from its locked position, when the shift has been completed, I provide the following mechanism: A controlling lever 55 is arranged on the cabinet of the machine opposite the controlling lever 34, and is likewise adjustably movable through frictional contact with a portion of the cabinet. It is preferably constructed with an accessible portion 56 and an angular extension 57 lying within the cabinet in the path of the pawl 51. The position of adjustment of this lever 55, therefore, determines the extent of shifting movement of the tone arm, or, in other words, the extent of repetition of the record. Its projecting end 57 will be engaged by the pawl 51, moving the latter to position for releasing the plunger and acting also as a buffer to prevent further swinging movement of the mechanism. The plunger when released will be moved first quickly within its dash-pot and then slowly on account of air compression, and the upper end of the bell crank 110 lever 46 and tone arm 15 are thus gradually lowered until the needle is again in engagement with the record. Simultaneously, with the first movement of the plunger, the frictional shoe is disconnected from the shifting 115 120 125 130 135 140 145 150 155 160 165 170 175 180

cam. A valve 58 is provided on the dash-pot for controlling the expulsion of air to thereby gage the speed of movement of the plunger, and a port 58^a, located in said dash-pot near the end of movement of the plunger, admits air to prevent the accumulation of a vacuum therein and consequent suctional return of the plunger.

Should it be desired at any time to dis-
10 continue the playing of the machine, either before or after a number of repetitions of the record have been made, the operator moves the controlling lever 55 to the right to its limit of movement, and in this position its arm 57 lies outside of a brake lever 59, which lies in a plane below the plane of pawl 5 and lever 57 as shown in Figs. 11 and 12. This lever is of bell crank construction, and extends to a position adjacent to the 5 usual controlling mechanism 60 of the phonograph, as best shown in Fig. 2. This controlling mechanism, it will be understood, consists of a friction disk 61 carried upon the governing shaft 62 and adapted to be en-
gaged by friction shoes 63, which shoes are adjustably movable through a speed controlling lever 64. The brake lever 59 has a turned end 65 adapted to engage with a right angular vane 66 formed upon the pivoted brake shoes. When the shiftable mechanism has swung outwardly to a position where the needle will be outside the periphery of the disk, the bracket or arm 43 will strike the adjacent end of an upwardly projecting toe 59' on the brake lever 59 and move it outwardly, thereby thrusting the end 65 of said lever in a direction to set the brakes on the governing device which, of course, will effectively stop the rotation of the turntable. The controlling lever 55, during this operation, may be so positioned outside the path of movement of the brake lever 59 as to engage with the releasing pawl 51, after the brake has been set, and the tone arm, therefore, will be allowed to lower its position at this time.

To prevent any possibility of the tone arm swinging inwardly, and also to assist in holding the brake, I provide a yielding locking device therefor in the form shown in Fig. 8, where it will be seen that a spring-pressed, pivoted pawl 67 is so positioned as to have its nose engage with the lower end of the bracket 43 when the latter is in its outward position of movement. This engagement between the bracket and pawl is a yielding one on account of the slanted arrangement of the engaging end 68 of the latter. The tone arm, however, will be held sufficiently positive to prevent accidental swinging or releasing of the brake, but a quick, manual thrust will disengage the parts and allow the mechanism to be swung inwardly, whereupon the turntable will automatically start its rotation and the operator needs only to set the needle to start the ma-

chine in playing operation. The usual stopping and starting lever may, therefore, be dispensed with.

The cycle of operation, briefly described, is as follows:

When the parts are in one position of adjustment, the tone arm arriving at a predetermined position is picked up by the tripping device, locked in raised position, and thereupon released from the tripping device. 70 The shifting mechanism coming into engagement drives the tone arm back to a predetermined starting position; the locking mechanism, at the end of the shifting movement, striking a stop which releases it and permits 75 the tone arm to fall by gravity. In so lowering itself, the friction clutch in the shifting mechanism is disengaged and air is compressed in the dash-pot, causing the arm and its needle to move slowly into playing en- 80 gagement with the record.

In the other position of adjustment, the stop is moved to position where it will engage with the tone arm when the latter is shifted outside the periphery of the record, 90 thereby exposing a brake device, which, when struck by the shiftable parts, is caused to be set; whereupon, further rotation of the record is prevented.

From what has been said thus far, it will 95 be seen that I have provided a phonograph which is entirely automatic to control its operation. If a user desires to have a record repeated, this may be accomplished by setting the tripping mechanism and the releasing mechanism in the proper relation, either before or during the playing of the machine. The adjustment of these parts is so fine that any portion of a record, such as a strain of 100 music or a phrase, may be marked out for 105 repetition. The tripping mechanism, obviously, is exceedingly accurate and not liable to disarrangement or breakage. The apex of the tripping lug is located on the central line of movement of the sliding block and consequently moves always in a radial line with the axis of the tone arm. The pendent trip-arm is likewise movable on a radial line from the center of the swinging tone arm, and when it engages the said lug these radial 110 lines coincide. Therefore, the strain imposed upon the lifting lever and the tone arm during the tripping operation is an end- 115 wise one such as to cause a clean vertical lifting movement of the tone arm without 120 liability of thrusting the latter to one side and scratching the record. The head of the actuating lug lies outside of the line of movement of its apex in a direction away from the pendent trip arm. Engagement 125 between these parts, therefore, is exceedingly accurate and refined. Moreover, the wedge-shaped construction of the tripping lug and the groove in the arm with which it engages insure a uniform position of tripping.

105

110

115

120

125

130

Owing to the yielding brushes 54 on the sector the shifting of the arm is accomplished quickly and without jarring movements. A cushioning effect is had at the beginning of the shifting movement on account of the bending of the brushes, and at the end of the shifting movement the strained bristles will act to hold the arm against any slight return movement and prevent rebounding of the same due to striking the stop lever 57.

To aid in the adjustment of the tripping device, I preferably provide a staff 69 carried upon the segment 32, with its upper end

70 in a position to engage with the bell crank lever 46 when the point of the tripping lug is in line with the groove in the pendent arm 39. The staff, therefore, acts as a sight to gage the adjustment of the trip device. Similar means may obviously be provided for assisting the operator in adjusting the position of the releasing device.

While I have shown and described but one form of my invention herewith, it is understood, nevertheless, that it is capable of many modifications and, therefore, changes may be resorted to in the construction and arrangement of the several parts without departing from the spirit of the invention as disclosed in the appended claims.

Having thus described my invention, what I claim and desire to secure by Letters Patent is—

1. In a phonograph, a record, a swinging tone arm carrying a reproducer, means carried by the tone arm to raise said reproducer from the record, means for controlling the raising of said reproducer at any point in the angular movement of the tone arm, means to retain the reproducer in raised position, means to shift the tone arm when the reproducer is raised, means to stop the return movement of the tone arm at any point and release the locking means to permit the reproducer to reengage the record.

2. In a phonograph, a record, a shiftable reproducing device therefor, adjustable means for causing the reproducer to repeat only a selected zone or part of the record.

3. In a phonograph, a record, a shiftable reproducing device therefor, means for causing the reproducer to repeat only part of the record, and means adjustable during the course of playing to permanently disconnect the reproducing device from the record.

4. In a phonograph, a disk record, a shiftable reproducing device therefor, means for automatically disconnecting said reproducer from any selected part of the record and returning the same to any selected part of the record to resume reproduction.

5. In a phonograph employing a sound record and a reproducing device therefor, a swinging tone arm carrying the reproducer, means on the tone arm operable to disen-

gage the reproducer from the record, and a constantly driven reciprocal member to engage with the means on the tone arm when the latter moves into its path for actuating said means to disconnect the reproducer from the record.

6. In a phonograph, a record, a reproducing device, lifting means for the reproducer, and a constantly driven reciprocal member to engage with the lifting means and disconnect the reproducer from the record, said reciprocal means being laterally adjustable to vary the point of disengagement of the reproducer.

7. In a phonograph, a motor, a rotatable record driven thereby, a reproducing device coacting with the record, freely adjustable means driven directly from the motor for raising the reproducer to disconnect it from the record at varying positions in the course of playing, and separate shifting means also driven by the motor for returning the reproducer to any desired position.

8. In a phonograph, a record, a swinging tone arm carrying a reproducer, means carried by the arm for raising the reproducer from the record, means comprising a constantly moving reciprocal member to engage with the lifting means and disconnect said reproducer from the record at variable points in the course of the swinging movement of the arm, and yielding driving means engageable when said reproducer is raised to return the tone arm to any desired position.

9. In a phonograph having a record and a reproducing device therefor and a swinging tone arm carrying the reproducer, means carried by the tone arm operable to disengage the reproducer from the record, and a reciprocating trip device concentrically adjustable about the axis of the tone arm and engageable with the means thereon for actuating the latter to disconnect the reproducer from the record.

10. In a phonograph, a record, a swinging tone arm carrying a reproducer, a radially slotted member, and a reciprocating trip device carried in said radially slotted member and adjustable about the axis of the tone arm for disconnecting the reproducer from the record.

11. In a phonograph, a record, a swinging tone arm carrying a reproducer, a trip device for disconnecting the reproducer from the record, said trip device having a reciprocal movement, and actuating means therefor comprising a power operated crank member.

12. In a phonograph, a record, a swinging tone arm carrying a reproducer, a trip device for disconnecting the reproducer from the record having a reciprocal movement, and actuating means therefor comprising a scotch yoke and a power operated crank arm.

13. In a phonograph, a record, a swinging

- tone arm carrying a reproducer, an angularly adjustable trip device for disconnecting the reproducer from the record having a reciprocal movement radial with the axis 6 of the tone arm, and means to preserve the radial movement of the trip device in all positions of its adjustment. 14. In a phonograph, a record, a swinging tone arm carrying a reproducer, a reciprocal trip device for disconnecting the reproducer from the record movable in a radial line with the axis of the tone arm, a quadrant concentric with said axis to permit angular adjustment of said trip device, 15 and an arcuate slotted reciprocating member for driving said trip device. 15. In a phonograph, a swinging tone arm, a bell crank lever carried thereby for raising said arm, a pendent arm on the bell 20 crank lever locked in one direction, and a reciprocating trip device to engage with said pendent arm to actuate the bell crank lever. 16. In a phonograph, a swinging tone arm, a lifting device on the tone arm, a 25 pendent arm on the lifting device having a swinging movement and locked in one direction and provided with a longitudinal groove, and a wedge-shaped reciprocal trip device to engage with the groove in said 30 pendent arm for raising the tone arm. 17. In a phonograph, a record, a swinging tone arm carrying a reproducer, means carried by the said arm for disconnecting the reproducer from the record, a member carried 35 by the tone arm and movable longitudinally thereof for actuating said disconnecting means, and reciprocal means for operating said link at a predetermined position in the angular travel of the tone arm. 40 18. In a phonograph, a record, a swinging tone arm carrying a reproducer, means for disconnecting the reproducer from the record, automatic shifting mechanism for the tone arm comprising a rotatable frictional 45 device and means on the arm to engage said frictional device when the reproducer is disconnected. 19. In a phonograph, a record, a swinging tone arm carrying a reproducer, means 50 for disconnecting the reproducer from the record, automatic shifting mechanism for the tone arm comprising a rotatable device formed with a series of bristles on its periphery, and means on the arm engageable 55 with said rotatable member when the reproducer is disconnected. 20. In a phonograph, a record, a swinging tone arm, carrying a reproducer, a reciprocal device, a rotatable shifting device, 60 means on said tone arm to engage with the trip device for raising the reproducer from the record, and a member on said raising means to engage with the rotatable device when the reproducer has been disconnected 65 for shifting the arm outwardly. 21. In a phonograph, a record, a swinging tone arm carrying a reproducer, means for raising the reproducer from the record and shifting the arm to position for retraversing the record, an automatically locking cushioning means to retain said reproducer in raised position, and adjustable means engageable by said cushioning means to release the same and permit said arm to lower gradually to reengaging position with the record. 70 22. In a phonograph, a record, a swinging tone arm carrying a reproducer, means for raising the reproducer from the record and shifting the arm to position for retraversing the record, and automatically locking cushioning means carried by the tone arm to retain the reproducer in raised position, and means engageable by the cushioning means to release the same and permit the reproducer to gradually reengage with 80 the record, said cushioning means comprising a plunger and a cylinder. 23. In a phonograph, a record, a swinging tone arm carrying a reproducer, means for raising said reproducer, locking said reproducer in raised position clear of the record, automatic means for shifting said arm in a return direction, and adjustable means for releasing said locking means, said locking means comprising a cylinder, a 85 plunger therein, and a locking pawl for retaining the plunger in extended position. 24. In a phonograph having a record and a shiftable reproducing device, automatic means for disconnecting the reproducing device from the record comprising lifting means, an air-compressing plunger connected with the lifting means and movable outwardly when the reproducer is raised from the record, a locking device to hold the 100 plunger in an outward position, whereby to retain the reproducer in disengaged position, and adjustable means to release said locking device to permit the reproducer to be lowered gradually into reengagement 105 with the record. 25. In a phonograph, a swinging tone arm carrying a reproducer, a record, and automatic means for raising, shifting and lowering said reproducer to repeat the record, 110 said means comprising an adjustable, reciprocating trip device, a lift arm carried by the tone arm, means on the lift arm to engage with the trip device for raising said reproducer, an air compressing plunger 115 movable with said lift arm, means for locking said plunger to retain the reproducer in raised position, a rotatable shifting device, means connected with the lift arm to engage with said shifting device, and an 120 adjustable releasing device to unlock said plunger to permit the tone arm to lower when it has been shifted. 26. In a phonograph, a rotatable disk record, a swinging tone arm carrying a re- 125 130 135

- 8
- producer, automatic disconnecting means for the reproducer, shifting means for the tone arm, and means engageable by the arm when the reproducer has been shifted to position outside the periphery of the record to stop the movement of the record, said means comprising a brake lever, against which the tone arm is thrust by the action of the shifting means, and a friction brake device operated by said lever, and means movable into position in front of said brake-device to interrupt the shifting of the tone arm and cause said reproducer to reengage the record for repeating purposes.
- 15 27. In a phonograph, a rotatable disk record, a swinging tone arm carrying a reproducer, means for disconnecting said reproducer from the record and shifting the same to position outside the periphery of the record, a friction brake device operable by the thrust of the arm in its latter position, said brake device being automatically releasable when the tone arm and reproducer are moved to playing position, and means movable into position in front of said brake-device to interrupt the shifting of the tone arm and cause said reproducer to reengage the record for repeating purposes.
- 20 28. In a phonograph, a rotatable record, a swinging tone arm, carrying a reproducer, means for raising said reproducer from the record, means for shifting the reproducer to position outside the periphery of the record, a brake device operable by the thrust of the arm when the latter is moved outwardly to stop the movement of the record, and means movable into position ahead of said brake device for returning the reproducer into playing position.
- 25 29. In a phonograph, a record, a shiftable reproducing device, a brake device means for automatically disconnecting said reproducing device from the record, means for shifting said device outside the periphery of the record, means for stopping the action of the record when the reproducer is in its latter position, and means freely adjustable during the operation of the phonograph movable into position in front of the brake device to interrupt the shifting movement of the tone arm and cause said reproducer to reengage the record for repeating.
- 30 30. In a phonograph having a record and a shiftable reproducing device for playing the said record, automatic means for manipulating the reproducer in a manner to continually repeat the playing of any portion of the record, said means being fully adjustable during the playing operation to render the same operable to move the reproducer to a position where it will be permanently disconnected from the record and incapable of further playing the record.
- 35 31. In a phonograph a shiftable reproducing device, a rotatable record, means for automatically starting the said record when the reproducing device is moved to playing position, means adjustable during the course of playing for causing said reproducing device to automatically repeat the playing of the record, said means being also freely adjustable during the operation of the phonograph to permit the reproducing device to be shifted to non-playing position, and means operable by the thrust of the reproducing device in the latter position to stop the rotation of the record.
- 36 32. In a phonograph, a swinging reproducer having movement about vertical and horizontal axes, a trip device movable radially with respect to the vertical axis of said reproducer, and a radially movable lifting device connected to said reproducer to engage with the trip device for raising said reproducer.
- 37 33. In a phonograph, a swinging reproducer having movement about vertical and horizontal axes, a trip device movable radially with respect to the vertical axis of said reproducer, a radially movable lifting device connected to said reproducer to engage with the trip device and raise said reproducer, and an automatic shifting device for said reproducer.
- 38 34. In a phonograph, a swinging reproducer having movement about vertical and horizontal axes, a trip device therefor movable radially with respect to the vertical axis of said reproducer, a radially movable lifting device connected to said reproducer to engage with the trip device, an automatic shifting device for said reproducer, and means carried by said lifting device to throw the shifting device in operation.
- 39 35. In a phonograph, a swinging reproducer having movement about vertical and horizontal axes, a trip device therefor movable radially with respect to the vertical axis of said reproducer, a radially movable lifting device connected to said reproducer to engage with the trip device, and means for shifting said reproducer.
- 40 36. In a phonograph, a swinging reproducer having movement about vertical and horizontal axes, a trip device therefor movable radially with respect to the vertical axis of said reproducer, a radially movable lifting device connected to said reproducer to engage with the trip device, an automatic shifting device for said reproducer, and a locking device for said lifting device, said locking device including a dish-pot, a plunger, and means for releasing said locking device at a predetermined position in the course of the shifting movement.
- 41 37. In a phonograph, a tone arm movable about a vertical axis and carrying a reproducer, means on said tone arm for raising the reproducer, and adjustable operating means for said raising means engageable

therewith at varying positions in the angular movement of the tone arm and arranged to apply its thrust movements on a line parallel with the longitudinal axis of the

5 tone arm at all times.

38. In a phonograph, a tone arm movable about a vertical axis and carrying a reproducer, attenuated means carried by the tone arm for raising the reproducer, said means 10 being movable along a line parallel with the longitudinal axis of the tone arm, and an attenuated reciprocal member movable in a

path radially with respect to the axis of said tone arm and operable to contact with said raising means when the two are in alignment to raise said reproducer. 15

In testimony whereof I have hereunto set my hand in the presence of two subscribing witnesses.

EDWARD L. HOLMES.
